DUSTPAN

Edward J. Duhaime, Brooklyn, N. Y., assignor to
 Robert S. Rodier and Robert F. Rodier, copart-
 ners, doing business as Hudson Molded Prod-
 ucts, White Plains, N. Y.

Application June 29, 1946, Serial No. 680,456

1 Claim. (Cl. 65—20)

1

This invention relates to dust pans, being particularly adaptable for manufacture of a plastic material such as, for instance, Lucite, polystyrene, or other suitable plastic, and aims to provide certain new and useful features of construction and operation whereby the utility and efficiency of the dust pan are enhanced.

Another object of the invention is the provision of novel features whereby the accumulated dust in the pan may be disposed of into a waste container in a reduced stream, thereby eliminating the possibility of having any of the matter drop outside the container onto the floor.

The above general as well as additional and more specific objects will become apparent in the following description, wherein characters of reference refer to like-numbered parts in the accompanying drawing. It is to be noted that the drawing is intended for the purpose of illustration only, and that it is neither desired nor intended to limit the scope of the invention necessarily to any or all of the exact details of construction excepting insofar as they may be deemed essential to the invention.

Referring briefly to the drawing, Fig. 1 is a plan view of a dust pan embodying the invention.

Fig. 2 is a side elevational view of the same.

Fig. 3 is a plan view of the dust pan with the pivoted door thereof in opened condition.

Fig. 4 is a sectional view taken on the line 4—4 of Fig. 3, with the door omitted.

Fig. 5 is a sectional view taken on line 5—5 of Fig. 1.

The dust pan comprises a substantially S-shaped base 10, having the trough 11 at the rear, and the crest 12 at the front. The rear wall 13 rising from the trough 11, extends higher than the crest 12, and its upper edge is a straight, flat surface. On one side a side wall 14 is provided, whose lower edge conforms to the shape of the base 10 and whose upper edge lies in the same plane as the upper edge of the rear wall 13. On the other side the side wall comprises two sections, the section 15 being fixed to the base 10 and being similar to the forward portion of the wall 14, and the section 16 which constitutes a door hinged at 17 to the section 15 so that, when the door is lifted as shown in Fig. 2, the wall on that side is opened at the trough 11.

The door 16 is semi-disc-like in outline, with its curved lower edge circular. The wall 13 of the base 10, however, is, although arcuate, not of the same radius of curvature as the trough, as is obvious, but rather bends inward. As a result,

2

since the curved lower edge of the door is of the same degree of curvature as the trough, the rear-most portion of the lower edge of the door would meet the upper inner surface of the wall 13 in closing the door and thereby prevent the curved lower edge of the door from fitting snugly into the trough. To permit of closing of the door, therefore, a downwardly tapering groove 18 is cut into the said surface of the wall 13, with the rear wall 19 of this groove a continuation of the curve of the trough 11. Thus, when the door is closed, the greater portion of its curved lower edge will register against the surface of the trough 11 and the rear portion of its lower edge will register in the groove 18 against the inner surface 19 thereof. Thus, when the door is closed, the side walls of the groove 18 serve to prevent sidewise movement of the door.

The upper edge 23 of the door 16, which is straight and also adapted to lie in the same plane as the top of the wall 13 when closed, is provided with a rearward extension or tongue 21 and a slot 22 between the tongue and the door body. When in closed position, the tongue extends through the transverse slot 20 through the wall 13 above the groove wall 19, with the top of the latter registering in the slot 22. The forward edge of the base 10 is beveled, substantially as shown at 24. A handle 25 is provided on the rear wall 13, and it may have a hole 26 therethrough for hanging the pan on a hook or the like.

The entire dust pan, with the exception of the door and its pivot pin, may be molded in a single piece out of a suitable plastic material, and of course the door 16 would also be made of a single piece of the same material. In use, the pan is held with the beveled edge 24 flush with the floor, and dust is swept onto the pan in the usual manner. To empty the pan, the dust is brought into the trough 11, the pan is tilted to bring the door end of the trough close to the waste container, and the door is opened, whence the dust will fall, or may be swept, out of the pan into the container. In that way there is little likelihood that any of the dust or waste on the pan will inadvertently be dropped anywhere excepting into the container.

Obviously, modifications in form and structure may be made without departing from the spirit and scope of the invention.

I claim:

A dust pan comprising a base substantially S-shaped in cross-section thereby providing a trough at the rear and a crest at the front, the

rear upper portion of said base being deformed in an inward direction with respect to the axis of said trough and constituting the rear wall of the pan, said pan having side walls, one of said side walls having a cut-out therethrough at one end of said trough, a door pivotally secured to said last-named wall and having its lower edge curved at a constant radius of curvature equal to the radius of curvature of said trough, said rear wall having a downwardly tapering groove cut there- 10 into, the base of which is a continuation of the circular curvature of said trough, said door when closed having the greater portion of its curved lower edge registering against said trough and the remaining portion of said lower edge adja- 15 cent said rear wall registering in said groove.

EDWARD J. DUHAIME.
